UNITED STATES PATENT OFFICE.

WILLIAM E. PINCKNEY, OF CHICAGO, ILLINOIS.

CARBURETER.

SPECIFICATION forming part of Letters Patent No. 603,431, dated May 3, 1898.

Application filed April 10, 1897. Serial No. 631,623. (No model.)

To all whom it may concern:

Be it known that I, WILLIAM E. PINCKNEY, a citizen of the United States, residing at Chicago, in the county of Cook and State of Illinois, have invented certain new and useful Improvements in Carbureters; and I do declare the following to be a full, clear, and exact description of the invention, such as will enable others skilled in the art to which it applies to make and use the same, reference being had to the accompanying drawings, and to the letters of reference marked thereon, which form a part of this specification.

The invention relates to that class of carbureters in which air or gas which it may be desired to further enrich is passed through a body of hydrocarbon, such as gasolene, so that it becomes carbureted as it bubbles up through the liquid.

The invention has for one of its objects the provision of means for regulating the distance through which the vapor to be enriched shall pass through the liquid hydrocarbon.

An additional object is to provide improved means for distributing or subdividing within the liquid body the vapor which is to be enriched.

The objects are obtained by the various parts and arrangement of parts, as herein-after fully set forth, and as illustrated in the accompanying drawings, in which—

Figure 1 is an elevation, partly in section, of the carbureter and its appurtenances. Fig. 2 is a sectional view, partly in elevation, on the line 2 2 of Fig. 1. Fig. 2^a is a sectional view of a modified form of the valve-regulating mechanism. Fig. 3 is a bottom plan view of the air-distributer, and Fig. 4 is a sectional view on the line 4 4 of Fig. 3.

Devices of this kind are usually employed for domestic service, and consist of a reservoir and a carbureting-chamber, together with suitable filling and distributing pipes, all of which are usually located in a specially-prepared subterranean chamber upon the premises of the user. In the present case the reservoir consists of a plurality of cylinders A A, horizontally disposed. While in the machine forming the subject of this application it is of less importance than in most machines of this type, I prefer to use a plurality of hori-

zontally-disposed cylinders as a reservoir in order that the level of the liquid may not change through a very extended range as the reservoir is emptied. The cylinders A A are 55 filled by means of a U-shaped pipe B, the outer end of which is intended to be convenient of access and is closed by a screw-cap b. The bow of the U is lower than either the reservoir or the carbureting-chamber and enters the former through the bottoms of the tanks A. The carbureter proper is a cylinder C, preferably vertically disposed and supplied with hydrocarbon by means of a pipe D, leading from the reservoir. This pipe may, 65 as shown, branch off from the filling-pipe B. A valve-casing E is incorporated into the pipe D and has a transverse and vertically-aper-tured diaphragm or partition e, the aperture of which is controlled by a downwardly-opening valve F. A cylinder G leads upwardly from the valve-casing E and is open to the interior thereof upon the same side of the partition e as the cylinder C. A float f is located within the cylinder G and is connected 75 with the valve F by means of the stem f', so that when the liquid has reached the desired level in the cylinder C it lifts the float and closes the valve F, cutting off the further supply to the cylinder C until the level of the 80 liquid therein has been lowered. The upper end of the cylinder G is vented to the cylinder C, as shown at g.

Air or other vapor which it may be desired to enrich is delivered to the machine under 85 pressure through a pipe H, which is provided with an ordinary check-valve, as indicated at h, for the purpose of checking back pressure. The pipe H enters a casing J, extending upwardly from the top of the cylinder C, and 90 reaches the latter through a tube K, which extends upwardly through the casing J and has lateral openings, as k, for the induction of the air, such openings being located between a lower and an upper stuffing-box j j', 95 crossing the casing J. A suitable bearing-block k' is located within the cylinder C for steadyng the lower end of the tube K. Any desired form of air-distributer, as L, may be applied to the lower end of the tube K. For 100 this purpose I use a disk M, of sheet metal, having a central aperture inclosed by a later-

ally - extending internally - screw - threaded flange adapted to a suitable screw - thread formed upon the exterior of the tube K, the disk M also having a downwardly-projecting

- 5 peripheral flange *m*. A strip of sheet metal P of greater width than the flange *m* is coiled to spiral form and attached along one of its edges to the under face of the disk M, the inner end *p* of this coil being located near, but 10 not in contact with, the pipe K, and the outer end *p'* being located near, but not in contact with, the flange *m*, so that a convolute passage P' is provided, leading from the tube K and terminating within the flange *m*. Baffle- 15 plates Q are located across the passage P' and are as numerous as the judgment of the maker may dictate. These baffle - plates extend downwardly from the disk M a short distance. The flange *m* is preferably provided with an 20 annular series of small apertures *m'* near its lower edge. The pipe K extends below the disk M, but need not, and preferably does not, extend below the coil P.

A rack R is secured to the upper end of the 25 tube K and is in alinement therewith, this rack coöperating with a pinion *r*, mounted upon a horizontal shaft S, journaled in a suitable bearing carried by a bracket-hanger *s*, projecting upwardly from the casing J. The 30 shaft S leads to any convenient place, such as the basement of a dwelling in connection with which the machine is used, and is provided with a hand-wheel *s'* or other means by which it may be rotated for the purpose of 35 raising and lowering the tube K. As the shaft S may be of considerable length and passes through the ground, I preferably inclose it within a tube *s*², within which it is free to turn. Any other means for shifting 40 the tube K may of course be employed.

A delivery-pipe O leads from the top of the carbureting-cylinder C to any suitable distributing system. A vent-pipe U connects the reservoir A A with the upper portion of 45 the cylinder C, so as to equalize the pressure within the two chambers. A pipe T leads downwardly from the bottom of the cylinder C, and returning extends upwardly, its upper end being convenient of access and being 50 closed by a screw-cap *t*. A pump may be applied to the pipe T for the purpose of cleaning the cylinder C.

In this type of machine the richness of the 55 gas delivered from it depends not only upon the distance through which the vapor to be carbureted travels through the liquid hydrocarbon, but also upon the specific gravity of the latter, the lighter or higher grades of gasoline being much more volatile than the heavier or lower grades, so that when a high grade of gasoline is used the vapor needs to travel a shorter distance through the liquid than when a low grade is employed, and hence in order that the gas delivered from the machine may 60 be of uniform quality it is essential either that

the gasoline shall be strictly of a uniform grade or that means be provided for introducing the air at various depths within the liquid body.

It is found in practice that commercial 70 gasoline varies greatly in specific gravity notwithstanding its accredited test. It is also found that in any considerable quantity, such as a barrel, there is a material difference in the specific gravity between the top and 75 the bottom. For these reasons unless special means are provided for adapting the machine to the particular quality of the material being used there will be a constant variation in the quality of the gas. 80

By filling the reservoir from the bottom I pass the new supply through any which may remain in the reservoir, thereby fairly intermingling the new charge with the old. By maintaining the liquid in the carbureting- 85 cylinder at a uniform level the air or vapor is uniformly treated and the resultant gas is of uniform quality unless the density of the liquid varies. Should the character of the flame produced indicate that too much or too 90 little hydrocarbon is being taken up, the tube K may be shifted so as to raise or lower the distributor L, thereby exposing the vapor to the liquid hydrocarbon a shorter or a longer time. The pipe K may be given a considerable range of movement, the stuffing-box *j*² being spaced apart a sufficient distance, so 95 that the lateral openings *k* will always be inclosed between them.

The action of the special form of distributor shown is as follows: Gasoline will enter the passage P' until the lower edges of the baffle-plates Q are submerged, leaving air-pockets between the baffle-plates and a quantity of air around the lower end of the tube 100 K and also inside of the flange *m*. Vapor entering through the pipe K will rise around its lower end until checked by the disk M and will follow the channel P' to the first baffle-plate Q. The vapor accumulating forces down the gasoline below the level of this baffle-plate, when 105 the augmenting pressure is communicated to the space between the first and second baffle-plates, crowding the air therein under the second plate into the succeeding pocket, and 110 so on until the annular passage beyond the coil is reached. As the volume of vapor is increased within this annular passage the gasoline is crowded back until the vapor reaches and escapes from the aperture *m'*. If 115 desired, these apertures may be dispensed with, as the vapor will be forced back and escape under the edge of the flange *m*; but inasmuch as it may not be desirable to provide for such a nicety of construction that the 120 lower edge of the flange *m* will be in a strictly horizontal plane I prefer to use a large number of small vent-holes, so as to better distribute the vapor and prevent all danger of 125 it escaping at one side of the distributor, and 130

hence in large volume. By employing the vent-holes the vapor is discharged from the distributor in small streams and bubbles up through the liquid in small globules, thus 5 greatly increasing the area exposed directly to the liquid. The baffle-plates Q may be dispensed with; but by their use the vapor is caused to dip repeatedly into the liquid. This distributor by securing a much more intimate intermixing of the vapor with the liquid than has heretofore been accomplished need not be submerged to great depth.

It will be seen that by the construction shown the reservoir may be filled and the carbureting-cylinder cleansed of any accumulation 15 of impurities without interrupting the carbureting operation and without the loss of any of the gas. The service-pipe D enters the cylinder C below the lowest point ever 20 reached by the distributor L, so that vapor introduced through the latter will not find its way into the reservoir through this tube.

In lieu of the float for controlling the valve F, I may use a flexible diaphragm f^2 , to the 25 center of which the valve-stem f' is securely attached and which is clamped between the meeting edges of a pair of concave plates G' g' , forming a casing which is mounted at the top of and is open to the cylinder G. When 30 this device is used, it will close the valve by upward pressure upon the diaphragm when the level of the liquid in the cylinder C is above the plane of the diaphragm. By constructing the parts of light material the diaphragm is very sensitive and is raised by 35 slight pressure. When the diaphragm is in its normal position, the valve is open.

A great advantage is obtained in carbureters of this class by delivering the liquid to 40 the carbureting-cylinder near its lower end for the reason that the liquid increases in density as it is acted upon by the air, its lighter portions being taken up by the air before its heavier portions are liberated, and as 45 the liquid enters at the bottom of the cylinder it rises and becomes intermixed with that already in the cylinder, thus tending to keep the density more nearly uniform, and consequently securing a greater uniformity in the 50 quality of the gas. In the carbureters heretofore made the service of the liquid has been to the top or upper portion of the carbureting-chamber above the point at which the air or vapor is admitted, and as a result the 55 latter has circulated through the liquid in the reservoir and reduced its specific gravity simultaneously with that contained in the carbureting-cylinder. By preventing the circulation of the vapor through the liquid in 60 the reservoir I provide for a constant feed of fresh hydrocarbon to the carbureting-cylinder until the entire supply has been ex-

hausted, in this manner also contributing to the uniformity in the quality of the gas.

I claim as my invention—

1. In a carbureter of the class described the combination with a carbureting-cylinder, of a casing projecting upwardly from the cylinder, and having a pair of stuffing-boxes spaced apart, a vertically-adjustable vapor-induction pipe entering the cylinder through such stuffing-boxes and having lateral apertures located between said boxes, and a service-pipe entering such casing between the stuffing-boxes.

2. In a carbureter of the class described, the combination with a carbureting-cylinder, of a casing projecting upwardly from the cylinder and having a pair of stuffing-boxes spaced apart, of a vertically-adjustable vapor-induction pipe entering the cylinder through the lower stuffing-box and being open to the interior of the casing thereabove and having a stem extending through the upper stuffing-box, and a service-pipe entering such casing 75 between the stuffing-boxes.

3. In a carbureter of the class described, the combination with a carbureting-cylinder, and a vapor-induction pipe entering the cylinder, of an imperforate radial disk at the inner end 80 of the tube and having a pendent annular perforated flange.

4. In a carbureter of the class described, the combination with a carbureting-cylinder, and a vapor-induction pipe entering the cylinder 85 and arranged to have its discharge end submerged within the liquid, of an imperforate radial disk at the inner end of the tube and having a pendent annular flange, and a pendent spiral flange within the annular flange.

5. In a carbureter of the class described, the combination with a carbureting-cylinder, and a vapor-induction pipe entering the cylinder, of a radial disk at the inner end of the tube and having a pendent annular flange, a pendent spiral flange within the annular flange, 90 and pendent baffle-plates crossing the upper portion of the convolute passage inclosed by the turns of the spiral flange.

6. In a carbureter of the class described, the combination with a carbureting-cylinder, a reservoir and a passage connecting the two, of a valve for controlling the passage, means for automatically actuating such valve to maintain the liquid in the cylinder at a uniform level, and a vertically-adjustable vapor-induction tube entering the cylinder.

In testimony whereof I affix my signature in presence of two witnesses.

WILLIAM E. PINCKNEY.
